(57) **CLAIM**

The ornamental design for a respiratory mask, as shown and described.

DESCRIPTION

FIG. 1 is a perspective view of a respiratory mask showing our new design.

FIG. 2 is an additional perspective view of the respiratory mask in accordance with our new design.

FIG. 3 is a front view of the respiratory mask shown in FIG. 3.

FIG. 4 is a side view of the respiratory mask shown in FIG. 1. The opposite side is similar and not separately illustrated herein.

FIG. 5 is a top view of the respiratory mask shown in FIG. 1.

FIG. 6 is a back view of the respiratory mask shown in FIG. 1; and,

FIG. 7 is a bottom view of the respiratory mask shown in FIG. 1.

The broken line showing is for illustrative purposes only and forms no part of the claimed design.
